UNITED STATES PATENT OFFICE.

CHARLES JAMES HATHAWAY, OF WALSALL, ENGLAND, ASSIGNOR TO FRANK PEROY
AULT AND HOWARD GLADSTONE AULT, OF WEST BROMWICH, ENGLAND.

TOBACCO-POUCH AND PURSE.

1,169,639.

Specification of Letters Patent.

Patented Jan. 25, 1916.

Application filed September 4, 1914. Serial No. 860,861.

To all whom it may concern:

Be it known that I, CHARLES JAMES HATHAWAY, subject of the King of Great Britain, residing at 114 Lichfield street, Walsall, in the county of Stafford, England, have invented certain new and useful Improvements 5 in Tobacco-Pouches and Purses, of which the following is a specification.

The invention relates to receptacles, and 10 particularly to that type of receptacle commonly used as a tobacco pouch or money purse, having for its main object the provision of a simple device of this character of a novel construction.

15 Another object of the invention is to produce a pouch or purse which may have its entire inner area or containing pocket filled to its full extent and which may be closed to tightly seal the contents therein.

20 With the above objects in view, the invention consists in a certain novel arrangement, construction and combination of parts hereinafter more fully described and finally pointed out in the appended claims.

25 Figure 1 is a front elevation of a tobacco pouch closed. Fig. 2 is a transverse section of Fig. 1 on the dotted lines A. Fig. 3 is a like cross section to Fig. 2 but with the pouch open. Fig. 4 is a front elevation 30 similar to Fig. 1 but with the outer flap thrown back to illustrate the inner flap. Fig. 5 is a front elevation of a different shape suitable for a purse and in a closed position. Fig. 6 is a similar front elevation as Fig. 5 but with the outer flap thrown back. Figs. 7, 8 and 9 are front elevations 35 of a pouch showing respective positions closed, outer flap thrown back, and outer and inner flaps thrown back, this arrangement having additional folding pieces 40 attached to both flaps to close over the opening in the side of the pouch.

With reference to Figs. 1 to 4 α is the completely closed side of the pouch, α^2 are the 45 completely closed boundary edges, and c is the opening side provided by the flap c^2 cut from the middle part of the material of said side to form and fit the opening c^3 in the manner shown in the drawings, particularly by Figs. 3 and 4. The end edges c^4 c^5 of the flap c^2 , which is the inner flap hereinbefore referred to, are permanently connected to the end edges d d of the opening c^3 by foldable side pieces or gussets e 55 and forming with the flap, c^2 , when the

pouch is open a definite mouth or entrance to the opening c^3 . The upper and free edge of the flap c^2 is provided with an extension c^6 adapted, when said flap is closing the opening c^3 , to tuck under the upper edge d^2 60 of said opening to assist in holding the inner flap in position and to close the opening at this edge. A tab f is attached to the flap c^2 for hand use in pulling out the flap. The flap c^2 instead of being cut from the side 65 c may be a separately formed attached piece, enabling a flap of different color to the sides of the pouch being used. The outer or external hinged flap g is a piece attached at g^2 to the opening side to, when the pouch 70 is closed, lie over and entirely cover the inner flap c^2 and the opening c^3 , as shown in Figs. 1 and 2, and to throw back when opening the pouch in the manner shown by Figs. 3 and 4. This external flap carries 75 at its opposite lower corners the snap button members g^3 and g^4 , to engage corresponding snap button members h on the opening side c , to fasten the external flap down over the inner flap and opening, as 80 clearly shown in Figs. 1 and 2. Any number of such snap buttons may be used.

Figs. 5 and 6 show the same construction as Figs. 1 to 4 but in a different shape and of smaller size, suitable as a purse. The 85 external flap is at g and the internal flap at c^2 , and the opening in the side c at c^3 , the flap c^2 being in this arrangement formed with a pocket α for gold coins or tickets.

The arrangement of pouch Figs. 7 to 9 90 is the same as Figs. 1 to 4, except that the folding pieces e extend across both flaps c^2 and g at the end edges, and fold over each other, and over the opening c^3 , and also with the two flaps, instead of folding gusset-like. 95 The dotted lines y Fig. 9 indicate how a folding piece opens. In this arrangement the parts g^3 g^4 of the snap buttons are carried by the folding pieces and the counterparts h h of said buttons by the inner flap. 100

Having now described my invention what I claim and desire to secure by Letters Patent is:—

1. A pouch or purse comprising side members secured together, one of said members 105 being formed with an opening, an inner flap adapted to close said opening, foldable pieces connecting said flap with the side edges of the opening, an outer flap adapted to close over and entirely cover the inner 110

flap and throw back, and means for holding the outer flap in its closed position.

2. A receptacle comprising side members secured together to form a containing chamber therebetween, one of said members being formed with a slit forming a flapped opening therein, the flap of said opening being adapted to close the latter, foldable gussets connecting the side edges of said flap with the edges of said opening, thereby forming a definite mouth-piece to said opening when the pouch is open, an outer flap carried by said receptacle and adapted to entirely cover said inner flap, and means for holding the outer flap in its closed position.

3. A receptacle comprising two side members connected together at the boundary edges thereof, one of said side members being completely closed and the other side member being formed with an opening, an inner flap cut from the material of said last-mentioned side member and adapted to provide said opening in said member, an extension provided on said flap and adapted to tuck under the upper edge of the opening,

gussets connecting the side edges of said flap with the edges of said opening, an outer flap adapted to close over and entirely cover the inner flap, and means for holding the outer flap in closed position.

4. A receptacle comprising two side pieces connected together all-around at the boundary edges thereof, one side piece being the completely closed side of the receptacle, while the other side piece is formed with a central opening, an inner flap carried by the side piece formed with said opening and of a size corresponding to said opening, flexible and foldable gussets connecting said flap with the edges of said opening, an outer flap adapted to close over and entirely cover the inner flap, and means for holding the outer flap in its closed position.

In testimony whereof I have hereunto set my hand in presence of two subscribing witnesses.

CHARLES JAMES HATHAWAY.
